LAMINATED BEAM FOR HAY STACKERS

George D. Moody, Portland, Oreg.

Application July 3, 1944, Serial No. 543,362

2 Claims. (Cl. 212—144)

This invention relates generally to hay making machinery and particularly to a laminated beam for hay stackers.

The main object of this invention is to provide an improved form of beam for hay stackers in which a rockable beam is pivotally mounted on a mast and provided with a hay fork at one end and an actuating line at the other end.

The second object is to provide a beam of the class described in which the beam is preformed throughout its entire length and laminated in order that the entire structure may be placed in tension before it is subjected to loading.

The third object is to utilize random lengths of lumber which are laminated into curved form by means of a waterproof glue and in which defects can be eliminated, thereby insuring a beam of uniform and reliable strength.

I accomplish these and other objects in a manner set forth in the accompanying specification as illustrated in the accompanying drawing, in which

Fig. 1 is a side elevation of the complete beam.

Fig. 2 is a plan of Fig. 1.

Fig. 3 is an end elevation of the beam with the cross braces removed for the sake of clearness.

Fig. 4 is an enlarged fragmentary view taken along the line 4—4 in Fig. 5.

Fig. 5 is a section taken along the line 5—5 in Fig. 4.

Similar numerals refer to similar parts throughout the several views.

Before entering into an explanation of this invention, it will be understood that beams resembling in appearance the one illustrated in this drawing have long been in use. Such beams have all been made of two sections joined at the fulcrum point and having the ends supported by cables and rods, whose tension is limited to the weight of the beams when empty or to the weight of the beams and load when loaded.

Such beams are inherently weak at the fulcrum point where they are subjected to severe reaction strains at the moment of unloading the hay fork, and to terrific strains if the operating line should break or the load has been too quickly released, causing a sharp rebound of the unloaded beam.

With the beam I am about to describe, a highly improved condition is set up in which all of the parts of the beam are under balanced stresses at all times and in which no injury can occur to the beam if suddenly unloaded.

Since the use of this stacker is so well understood, it will not be illustrated or described in detail in this application, other than to say that

5 a hay fork is mounted on the forked ends of the frame, the tines of which are commonly eight feet long and cover a beam of twelve feet in width. This fork may be dumped or reset from the ground at the foot of the mast upon which this beam is pivotally mounted. A block and tackle attached to the end of the A-frame is used to pull it down and of course raise the fork after the fork is loaded.

10 The fork is commonly loaded by bucking the hay onto the fork after which it is raised and the entire beam swung around on its pivot to a point above the stack upon which it is to be dropped. Stability is provided to the beam by curving its ends downwardly so that a line passing through the center of gravity of the load and to the point of application of the power would pass below the pivot point of the beam.

15 Referring in detail to the drawing, there is shown a pair of curved beams 10, which are united at one end 11 and spaced approximately eight feet apart at the other end, the entire beam 10 being in the neighborhood of thirty two feet.

20 The individual beams 10 are preformed of a plurality of laminations 12, preferably in the form of a curve formed by bending the end over an intermediate fulcrum point. The laminations 12 are glued and the bending is performed before the glue is set. At the point 11 is provided the angle 25 plates 13, which are secured to the beams 10 by the bolts 14. An eye bolt 15 extends through the plates 13, and its eye 16 is employed to fasten the tackle blocks of the operating mechanism (not shown).

25 The opposite end 17 of each beam part 10 is preferably reversely curved as illustrated, and is provided with a strap metal shoe 18 which terminates in an eye 19 adapted to receive an elongated pipe 20 which serves as a hinge for the hay fork 40 (not shown). The shoe 18 is secured to the end 17 by means of the bolts 21. Cross braces 22 and 23 are secured transversely across the frame parts 10, which are further reinforced by the diagonal braces 24.

30 At an intermediate point, which in common practice is approximately eighteen feet from the end 17 and fourteen feet from the end 11, are secured the angular brackets 25, whose sides 26 are secured to the beam part 10 by means of the bolts 27. From the angle plate 25 depends a standard 28, whose end 29 is rounded to fit into the recess 30 formed between the standards 31 on the plate 32 which, in turn, is secured by means of the bolts 33 to the bolster 34, which is adapted to rotate on the vertical pivot 35.

Each plate 25 extends inwardly from the inner side of the beam part 10 to form a footing 36 for the truss member 37. The two truss members 37 are inclined and united at their upper end by means of a bolt 38. A hole 39 is formed through the upper end of the truss members 37 to receive the rod 40, whose lower end is attached to the eye bolt 16 and whose upper end, which passes through the truss member 37, is provided with an eye 41 to which the two cables or rods 42 are secured, and from which they extend to the end 17 of each beam part 10 and are made fast to the ends 17 by means of the bolts 42A, or in any other manner.

It is desirable to provide turn buckles 43 in the rods 42 in order that the tension may be properly balanced and distributed throughout the device.

In some cases the plates 25 may have the footings 36 inclined as shown in Fig. 4, in which event it is desirable to form a double wedge 44 of hard wood whose top face 45 becomes the support for the beam 10 and the trusses 37.

While I have thus illustrated and described my invention, it is not my desire to be limited to the precise form shown herein, and I intend to cover

such forms and modifications of the invention as fall fairly within the appended claims.

I claim:

1. A laminated beam for hay stackers consisting of a pair of preformed laminated beam parts joined at one end and spaced at the other end thereof, and curved upwardly along the intermediate portion thereof, means for tiltably and rotatably supporting said beam parts along the upward portion thereof, and a truss over the pivotal point having truss rods extending from the top of same to the opposite ends of the beam parts.

2. A laminated beam part for hay stackers, consisting of an arcuate member composed of a plurality of superimposed laminations glued into a single beam part extending the full length of the completed beam and upwardly curved at the intermediate portion thereof, and an A-truss frame disposed at the high point of said beam frames, together with brace rods extending from the top of said truss to the opposite ends of the beam parts.

GEORGE D. MOODY.
